SEPARATOR HOOD FOR A COMBINE

Theodore H. Koeber, Barrington, and Robert A. Skyer,
Chicago, Ill., and Donald A. McCallum, Burlington,
Ontario, Canada, assignors to International Harvester
Company, Chicago, Ill., a corporation of Delaware

Filed Feb. 13, 1967, Ser. No. 5,773

Term of patent 14 years

(Cl. D40—1)

Fig. 1.

Fig. 2.

FIGURE 1 is a perspective view taken from the left-rear of the separator-hood showing our new design;

FIGURE 2 is a perspective view taken from the right-rear of the separator-hood showing our new design;

FIGURE 3 is a perspective view taken from the right side of the separator-hood showing our new design; and

FIGURE 4 is a perspective view taken from the rear of the separator-hood showing our new design.

The portions shown in broken lines on the drawings are included for illustrative purposes only.

We claim:

The ornamental design for a separator hood for a combine, substantially as shown and described.
